UNITED STATES PATENT OFFICE

2,643,738

PUMP ACTUATING SYSTEM FOR RAIL AND
FLANGE LUBRICATORS

Oscar F. Magnus, Chicago, Ill., assignor to American Brake Shoe Company, New York, N. Y., a corporation of Delaware

Application March 12, 1949, Serial No. 81,096

3 Claims. (Cl. 184—3)

1

The invention relates to railroad track equipment and, more particularly, to the lubrication of rails and the flanges of car wheels. The invention relates especially to the type of lubricator disclosed and claimed in Huber and Magnus application, Serial No. 600,326, filed June 19, 1945, now Patent No. 2,486,800, but is not necessarily limited to such use.

According to the prior application, the rail lubricator is operated by a spring-urged wheel-contacting plunger depressed by the treads of car wheels. Journaled at the rail is a drive shaft having an overrunning, friction drive clutch and an overrunning, friction check clutch. The drive clutch has an arm bearing against a lug on the plunger whereby reciprocation of the plunger is communicated to the clutch arm. A flexible shaft connects said drive shaft with suitable pumping apparatus mounted in a lubricant reservoir set into the ground alongside of the track.

The effective operation of the prior lubricator depends largely upon the fact that friction type clutches provide substantially instantaneously gripping regardless of the amplitude of movement applied to the clutch. In fact, under some conditions of operation, the amplitude of vibration of the clutch arm is of the order of only a degree or two, and the movement seems more like a tremble than a substantial reciprocation. The effective operation of the prior lubricator depends also on the fact that all reciprocating parts are located at the rail; that their number is kept at a minimum; that their mass is small; and that the amplitude of reciprocation is kept at a minimum.

It is an object of the present invention to further utilize these desirable characteristics. More instantaneous gripping is obtained by a new type of friction clutch which acts more on what might be called a toggle principle than on a wedging principle. Less mass is obtained by use of the new clutch and by suitable arrangement of the parts. Less amplitude is obtained by providing for smaller depression of the plunger. More positive spring action is obtained by the use of a multicoil torsion spring for holding the clutch arm in contact with the plunger lug. Improved adjustment of plunger movement is obtained by adjusting the height of the entire plunger housing with respect to the rail by a special shim carrier.

The present invention, in its preferred form, provides a housing secured to the running rail. Within the housing is a plunger compartment and a clutch compartment. The clutch compartment

2

is closed by a check clutch housing having an inwardly projecting hub. Within the check housing is a check body in which the drive shaft is journaled. The inboard side of the check body is provided with a cylindrical raceway in which is disposed a plurality of toggle elements, or sprags, operating between the outer cylindrical raceway and the cylindrical drive shaft. Also mounted on the drive shaft is a drive clutch body having a cylindrical raceway disposed adjacent the check raceway and having similar sprags operating directly against the drive shaft. Suitable retaining rings hold the respective sprags in position and a thrust collar spaces the respective clutch bodies apart. The reciprocating drive arm is secured to the drive clutch body. This drive arm carries a roller which bears against a lug on the plunger. A torsion spring surrounds the hub of the check clutch housing and has end projections disposed against suitable shoulders on the check clutch housing and on the drive clutch housing. The housing is adjustably mounted on the rail by shim carrier cages enclosing blocks through which the mounting bolts pass; shims located between the blocks and the cages determine the height of the housing.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part hereof, in which:

Fig. 1 is a fragmentary plan view, illustrating the lubricator of the invention applied to a running rail;

Fig. 2 is an elevation, on the line 2—2 of Fig. 1;

Fig. 3 is a cross section through the rail taken on the line 3—3 of Fig. 1;

Fig. 4 is a side elevation of a portion of the rail, showing the plunger mechanism applied thereto, the view taken on the line 4—4 of Fig. 1;

Fig. 5 is a section through the plunger mechanism, taken lengthwise of the rail, on the line 5—5 of Fig. 6;

Fig. 6 is a plan section of the plunger mechanism; taken on the line 6—6 of Fig. 5;

Fig. 7 is a vertical section of the plunger mechanism, taken on the line 7—7 of Fig. 5, showing an adjusting shim in position;

Fig. 8 is a vertical section through the drive and check clutches, taken on the line 8—8 of Fig. 5;

Fig. 9 is a vertical section through the check clutch, taken on the lines 9—9 of Figs. 8 and 12;

Fig. 10 is a vertical section through the drive clutch, taken on the lines 10—10 of Figs. 8 and 12;

Fig. 11 is a fragmentary perspective illustrating the delivery plate and equalizing distributing members;

Fig. 12 is an enlarged section through the overrunning clutches illustrating the details thereof;

Fig. 13 is a side elevation of a modified track lubricator, illustrating a preferred lubricant feed rate adjusting arrangement, in which the housing is adjustably mounted on the running rail by shim carriers;

Fig. 14 is a plan view, partly broken away, of the construction shown in Fig. 13;

Fig. 15 is a vertical section, taken on the line 15—15 of Fig. 13; and

Fig. 16 is a vertical section taken on the line 16—16 of Fig. 15.

In the following description and in the claims, various details will be identified by specific names for convenience, but they are intended to be as generic in their application as the art will permit.

Like reference characters denote like parts in the several figures of the drawings.

In the drawings accompanying and forming part of this specification, certain specific disclosure of the invention is made for purposes of explanation, but it will be understood that the details may be modified in various respects without departure from the broad aspect of the invention.

Referring now to the drawings, and more particularly to Figs. 1 to 3, the lubricator, according to the invention, comprises, in general, a delivery plate 16 secured to the side of a conventional T-rail 15; these members form a series of aligned delivery slots 17 for delivering lubricant to the flanges of wheels 24. Secured to the other side of rail 15 is plunger mechanism, indicated in general by 18, including a plunger 52 adapted to be depressed by the treads of wheels 24. The plunger mechanism 18 operates through the special clutch mechanism, explained more in detail hereinafter, to drive uni-directionally a flexible shaft 19 extending to a lubricant tank 21; tank 21 is set in the ground alongside the track and filled with lubricant.

The flexible shaft 19 drives a vertical chain 20 in the tank which in turn drives a series of gear pumps 22 located in the bottom of the reservoir 21. Three gear pumps 22 are shown for purposes of illustration; a lesser or greater number may be used. Each pump 22 delivers lubricant to its individual supply pipe 23 which passes through the tank wall and extends to the running rail 15 to deliver lubricant to the slots 17.

The rail 15 rests on suitable tie plates 26 which may be suitably canted in accordance with conventional practice; the tie plates 26 rest on conventional ties 25, as shown in Fig. 2. The rail 15 and tie plates 26 are suitably spiked to the ties 25 by spikes (not shown).

Referring now also to Figs. 4 to 10, the plunger mechanism 18 will now be described. This mechanism comprises a housing 28, which may be in the form of a casting; housing 28 comprises vertical end walls 29 and 35, plunger guide walls 32, 33, top wall 36, and bottom wall 37. 75

The end walls 29 and 35 have flanges 39. The back of the housing 28 is closed by a back plate 31 secured to end walls 29 and 35 by screws 34. The housing is disposed against a backing plate 27 which in turn is disposed against a filler plate 30. Flanges 39, backing plate 27 and filler plate 30 are connected to the rail 15 by bolts 38 which pass therethrough. The corners formed by end walls 29, 35 and top wall 36 are rounded as indicated in Fig. 5; end walls 29 and 35 converge outwardly toward front wall 40 as indicated in Fig. 6.

The vertical wall 33 divides the housing 28 into two compartments; viz, a plunger compartment 42 for plunger 52 and a clutch compartment 43 for drive clutch 68 and check clutch 80. Plunger compartment 42 has an opening in its front wall 40 closed by removable plate 47. Plate 47 is secured to the housing by a screw 49 which holds it in position between lugs 50 (Fig. 4). Plunger compartment 42 has a drain hole 44 at the bottom thereof extending through the front wall 40.

Clutch compartment 43 is closed by a check clutch housing 48 which is held in position by bolts 51 which pass through the check clutch housing 48 into plunger housing 28 (Fig. 4).

Plunger 52 has a rounded or beveled top 53, the surface of which may be suitably hardened to withstand the shock of engagement by wheel treads of high speed trains. Plunger 52 slides in vertical ways formed in guide walls 32, 33, front wall 40, back plate 31, and a hole in top wall 36. Stiff coil spring 54 seats in a recess 55 in the bottom of the plunger and surrounds a boss 55 on the bottom wall 37 to urge plunger 52 upwardly. Upward movement of the plunger is limited by a lug 57 (see Fig. 7) on the plunger engaging a shoulder 58 formed by the top wall of the plunger compartment opening.

A suitable shim 59 is interposed between lug 57 and shoulder 58 to adjust amplitude of plunger movement, as described hereinafter more in detail.

Referring now more particularly to Figs. 8, 9, 10 and 12, the overrunning friction drive clutch 68 and overrunning friction check clutch 80 will now be described. These clutches are mounted on drive shaft 61 journaled in bearing sleeve 62 fitted in check clutch body 63; the latter is secured within housing 48 by pin 64 fitting in half holes in the check housing 48 and check body 63.

The body 63 has an annular recess forming a raceway 65 in which are disposed a plurality of friction elements or sprags 69. The sprags are held in position by a retaining ring 66 set into check clutch body 63.

The drive clutch 68 includes an arm 90 having a hub or drive clutch housing 91. Fitted within hub 91 is drive clutch body 70; the latter is held in position by pin 75 fitted in half holes in hub 91 and in body 70. Fitted within body 70 is bearing sleeve 71 journaled on shaft 61. Body 70 has an annular recess forming a raceway 72 for sprags 74. A retaining ring 73 is set in clutch body 70 to hold the sprags 74 in place.

The entire clutch assembly is held endwise on shaft 61 by end washers 76 and 77; the latter are held in place by snap rings, indicated by 78, sprung in grooves in the shaft. A center thrust washer 79 separates retaining rings 66 and 73. It will be noted that the hub 91 of the arm 90 and the hub of the check clutch body 63 meet at the thrust washer 79. Both clutches may be suitably packed in lubricant.

The sprags 69 and 74 are identical in construction. They operate between their respective outer races 65 and 72, which are cylindrical, and the cylindrical surface of the shaft 61, which constitutes their inner races.

The relationship of the sprags and their inner and outer races is the same in each clutch, but the unidirectional action of the two clutches is opposite; in actual operation the outer race of the drive clutch 68 applies torque to the drive shaft 61 to drive the shaft uni-directionally, while the shaft of the check clutch 80 applies torque to its outer race 65 to prevent retrograde movement of the shaft, as will hereinafter appear.

Since the sprags are identical in construction, the details thereof are given the same reference characters. The sprags 69 and 74 are D-shape in end elevation as indicated in Figs. 9 and 10; they have rounded inner contact surfaces 81 and outer contact surfaces 82. The ends of the sprags have notches in which are disposed helical endless garter springs 84 which tend to expand.

The shape of the sprags and the action of the garter springs cooperate to urge the axes of the sprags (connecting the contact surfaces 80 and 82) toward a radial position with respect to the center of the shaft 61. Thus, as either the inner race or the outer race rotates in such direction as to urge the sprag axes toward radial position, the angle and co-efficient of friction is such as to lock the contacting surfaces 81 and 82 against their respective races, i. e. to provide a toggle action; and thus provide for the transmission of torque from either the outer race to the inner race, or vice versa; this is the driving condition of the friction clutches.

When the direction of either the inner race or the outer race with respect to the other race is in such direction as to urge the sprag axes away from radial position, the angle is such as to permit free movement of one race with respect to the other; this is the overrunning condition of the friction clutches.

For a more complete description of the construction and operation of this type of overrunning clutch, attention is called to Lund Patent No. 2,383,424, dated November 6, 1945, and Blair Patent No. 2,427,120, dated September 9, 1947.

Referring now to Figs. 5 and 6, the plunger 52 operates the housing arm 90 by a roller and cam mechanism. A roller 95 is journaled on pin 96 which is fixed in a fork 97 on the end of arm 90. Arm 90 projects through an opening in wall 33 toward plunger compartment 42. Roller 95 engages a cam surface 98 on lug 99 secured to the plunger 52. The arm 90 is sufficiently short that even with maximum amplitude of reciprocation of plunger 52, the roller never contacts the side wall 88 of the plunger.

A torsion spring 100 surrounds a hub on check clutch housing 48 and operates between an abutment 101 on arm 90 and a projection 102 on housing 48. Additional abutments 101 are provided on arm hub 91 and additional abutments 102 are provided on housing 48 against which the ends of torsion spring 100 may also be set to obtain the desired spring tension. The torsion spring 100 operates to hold the roller 95 constantly against the cam surface 98.

It will be understood that the passage of trains on the running rail 15 causes the plunger 52 to move vertically back and forth, being pushed

down by car wheels against the pressure of plunger spring 54. This causes cam roller 95 to execute a follower movement on cam surface 98, which oscillates drive arm 90 about shaft 61.

5 Due to the drive clutch 58 overrunning in one direction, the reciprocating movement of drive arm 90 causes uni-directional movement of shaft 61.

Shaft 61 drives the lubricant pumps in the 10 reservoir through linkage indicated particularly in Figs. 1, 2 and 8. Shaft 61 has secured thereto a universal joint 105 forming part of the flexible shaft 19. Universal joint 105 is connected to shaft 61 by sleeve 121. The other end of flexible shaft 19 has a universal joint 106 forming part 15 of sleeve 122 secured to shaft 115 journaled in the reservoir tank 21. The universal joints 105 and 106 are secured to stud shafts 108 and 109 surrounding which is a sleeve 107. Sleeve 107 is fixedly connected to shaft 108 but slidably connected to shaft 109, a bolt 110 passing through shaft 109 and slots 111 in sleeve 107.

The drive mechanism in the reservoir 21 comprises a sleeve 114 having a flange 113 bolted to the adjacent vertical wall of the reservoir 21. The sleeve 114 forms a bearing for shaft 115. A suitable sprocket is mounted on shaft 115 on which rides chain 20.

Located at the bottom of the reservoir tank 21 30 is a base 117 suitably spaced from the bottom of the tank by spacers 118. Bolted to base plate 117 are one or more gear pumps 22 of the type illustrated in Heidenthal Patent No. 2,185,810, dated January 2, 1940. These gear pumps 22 35 have their drive shafts in line and connected by suitable coupling members 129. The drive shaft of end pump 22 supports a sprocket on which rides chain 20.

The entire flexible shaft 19 may be covered 40 with a flexible synthetic boot 119 having felt- 45 bushed ends snugly fitting over sleeves 121 and 122. This keeps out dirt and permits the flexible shaft to be packed in grease.

Referring now to Figs. 1, 3 and 11, the delivery 50 plate 16 is clamped against the running rail 15 in such a way as to form a plurality of lubricant chambers 124 between the plate and the rail. The delivery plate 16 is clamped to the stock rail by a series of bolts 125. Gaskets 123 of soft material are located around the periphery of the grease chambers 124 to form grease-tight joints. Separate metal spacers 126 are located between the several gaskets. The bolts 125 pass through these spacers.

55 At the center of each chamber 124 a supply nipple 127 is provided. These nipples pass through openings in the reinforcing plate 30 and are threaded into the web of the rail 15. Each grease chamber 124 communicates with a dispensing slot or crevice 17. These slots or crevices form in effect a very long slot which is substantially continuous along the length of the rail, being interrupted only at the spacers 126.

The underside of the head of the rail 15 is cut 60 away to a length corresponding to the length of the lubricator. The underside of the rail head is planed "straight," i. e. to form a plane surface and the delivery plate 16 is also cut to form a corresponding plane surface. The connecting channels through which the lubricant flows are thus also "straight" from the point where they connect with the lubricant chambers 124 to the delivery slots or crevices 17. This "straight" planing of the rail not only simplifies machining, 65 but is effective in reducing rail failures.

To assist in uniform distribution of the lubricant along the length of the delivery slots 17, grease deflecting members 130 are provided. These deflecting members are in the form of separate strips anchored in grooves suitably machined in the delivery plate. The strips are held in position by screws 131.

The deflectors 130 have their maximum projection over the nipples 121 and taper toward their ends; this insures a more even and uniform distribution of the grease along the length of each individual delivery slot or crevice 17.

Referring now to Figs. 13 to 16, the form showing the preferred adjustment of lubricant feed rate will now be described. In this form, similar parts are indicated by the same numbers as corresponding parts in the main form, but with primes added.

Here the mounting flanges 39' of the main housing 28' are provided with vertical rectangular openings 135 in which are mounted shim carrier cages 136. The front wall of the shim carrier 136 is flanged on all four sides to overlap the opening 135 and has an elongate vertical slot 137 for bolt 139. The shim cage 136 has a back wall 138 which is also slotted for the bolt 139. The cage 136 is open at its sides. Within the cage 136 is a square block 140 having a hole through which the bolt 139 passes. A plurality of shims 141 are located at the top, and at the bottom, of the block 140, as indicated. The bolt 139 has a removable nut 142, a spring washer 143 and pressure plate 144. The manner of using this adjustment is described hereinafter.

Operation and comments

As the trains pass over the running rail 15, the wheel treads engage plunger 52, pressing it downwardly against plunger spring 54; torsion spring 100 urges roller 95 to follow cam surface 98. The oscillation of drive arm 90 drives main shaft 61 uni-directionally through overrunning drive clutch 68. The check clutch 67 being constructed to overrun oppositely from the drive clutch 68, prevents any retrograde movement of clutch shaft 61. Uni-directional movement of clutch shaft 61 is communicated through flexible shaft 19 and chain 20 to the several gear pumps 22 which deliver lubricant to the delivery plate.

In the form indicated, the overrunning clutches are set to drive the pumps 22 upon upward movement of the plunger 52, with clutch shaft moving in the direction of arrow A (Figs. 5, 9 and 10); this is the preferred form.

It will be understood that worn wheels cause false flanges indicated at 104 to be built up at the sides of the treads where they engage the plunger 52 and that the plunger 52 will be depressed different amounts depending upon the size of the false flange. Unequal depressions of the plunger will, in general, cause unequal oscillations of the clutch arm 90.

The relationship between the top of the plunger and the rail surface may be varied to provide different operations to control lubricant feed under different conditions. For example, a section of track having many heavy curves will need a larger rate of lubricant feed than a section of track having fewer and gentler curves. Ascending grades, other things being equal, will generally require less lubricant feed. Locations where trains regularly stop require less feed. In addition, there are the varying effects of high speed trains and low speed trains. Generally speaking, higher train speeds will operate the

present lubricator to feed more lubricant than slower speed trains. In addition, there are the different effects of new wheels and worn wheels. After a wheel is in use, a false flange is formed 5 on the tread opposite the true flange. The larger the false flange, the more the plunger is depressed.

In Figs. 1 to 12, lubricant feed rate may be adjusted by the use of different size shims 59 between the plunger lug 57 and shoulder 58. The size of the shim determines the upper (undepressed) position of the plunger and the corresponding lower position of the roll 95 on surface 98. The size of the shim determines the 15 upper limiting position of the clutch arm. The size of the false flange 104 determines the lower limiting position of the clutch arm. In general, the thicker the shim, the less the rate of lubricant feed, and vice versa.

To change the size of the shim, the adjusting plate 47 is removed and a shim 59 removed and another one of the proper size inserted between the plunger lug 57 and shoulder stop 58.

In Figs. 13 to 16, to adjust the height of the 25 main housing 28', it is only necessary to remove the nuts 142, washers 143 and plates 144, then remove the shim carriers 136 and blocks 140. The shims 141 are then easily accessible by sliding out the sides of the shim cages 136. The 30 necessary shims are transferred from beneath the block 140 to the top of the block 140, if it is desired to raise the housing; and vice versa, if it is desired to lower the housing. The parts are then replaced, as will be understood by those 35 skilled in the art.

With this type of adjustment, it is preferred to omit the adjusting shims 59, as shown in the first described form. This eliminates troubles due to battering the shims 59 by blows caused 40 by upward movement of the plunger, a condition sometimes occurring at locations handling high speed trains.

In general, the higher the position of the 45 housing 28' (and plunger) the greater the pumping action and grease feed; similarly, the lower the housing, the less pumping action. The adjusted position of the housing determines the lower limiting angular position of the clutch arm with any particular false flange size; the upper limiting angular position of the clutch arm remains the same, regardless of housing height.

Thus a track lubricator is provided in which the number and mass of reciprocating parts is reduced to a minimum. Only the plunger and drive arm and parts fixed thereto reciprocate. 55 The amplitude of movement and mass of these reciprocating parts is reduced to a minimum. Movement of the clutch drive shaft, of the flexible connecting shaft, of the chain, and of the pumps is uni-directional. Lost motion is 60 thus minimized. There are fewer points of operating impact. There is less wear, repair and maintenance. There is more accurate grease delivery.

The torsional clutch spring 100 surrounds the 65 hubs of both the check clutch housing and the drive clutch housing and operates to hold the follower roll 95 in firm engagement with the cam surface 98 under the rapid reciprocations of the plunger 52.

The friction sprags take hold substantially 70 instantly, without requiring any appreciable slipping movement to make the surfaces grip. Both the inner and outer races of the sprags are true cylindrical surfaces; this facilitates manu-

facture since they can be turned on an ordinary lathe. No special spiral or straight wedging surfaces are necessary on the races as are necessary with conventional overrunning friction roller clutches. The sprags operate directly upon the cylindrical surface of the drive shaft. The sprag construction permits the races of the drive and check clutches to be adjacently disposed. The body members of these races are journaled on the drive shaft and form seals for the sprags, facilitating exclusion of dirt. The check clutch body provides a journal for the drive shaft and the drive clutch body provides a support for the drive arm.

Since all parts of the uni-directional drive linkage are maintained in taken-up condition, the impulses applied by the first wheels of the train are immediately available to start the pumps rotating to deliver lubricant. Since all pressure on the lubricant immediately ceases after the last impulse is imparted to the plunger, after-feed of the lubricant is also minimized.

The shim carrier adjustment of the entire plunger housing provides a convenient adjustment in the track of lubricant feed to handle the different conditions of lubricator operation discussed above. It makes possible elimination of the plunger shims 59 and resulting troubles due to shim battering. The bodily removal of the shim carriers gives convenient access to the shims for adjustment. At the same time the shim adjustment does not interfere with tight clamping of the housing against the rail.

While certain novel features of the invention have been disclosed herein, and are pointed out in the annexed claims, it will be understood that various omissions, substitutions and changes may be made by those skilled in the art without departing from the spirit of the invention.

What is claimed is:

1. In a rail lubricator, operating mechanism actuatable by trains running on the track structure, said operating mechanism including a housing secured to the track structure, an operator movable in said housing, said housing having a mounting opening, a bolt passing through the

10

track structure and through said opening, and adjusting devices for adjusting the height of said housing, said adjusting devices comprising a shim located between said bolt and said housing.

5. 2. In a rail lubricator, operating mechanism actuatable by trains running on the track structure, said operating mechanism including a housing secured to the track structure, an operator movable in said housing, said housing having a mounting opening, a bolt passing through the track structure and through said mounting opening, a shim carrier cage disposed in said opening and through which said bolt passes, a block within said cage having an opening for said bolt, a shim located between the top of said block and the corresponding surface of said cage, and a removable nut on said bolt to hold said block and cage in position and to clamp said housing to the track structure.

3. In a rail lubricator, operating mechanism actuatable by trains running on the track structure, said operating mechanism including a housing secured to the running rail, a plunger slideable in said housing, said housing having mounting flanges at either end, bolts passing through the rail and through said mounting flanges; each said flange having a vertical opening, a shim carrier cage disposed in said opening, said cage having a back wall and a front wall and open at the sides, each wall being provided with vertical slots through which a bolt passes, a block within said cage and having an opening through which said bolt passes, shims located between the top and bottom of said block and corresponding surfaces of said cage, and a removable nut on said bolt to hold said block and cage in position and to clamp said housing to the rail.

OSCAR F. MAGNUS.
